UNITED STATES PATENT OFFICE

160,699

FLUSH MOUNTED INSTRUMENT CASE

Otto Fischer, Corona, N. Y., assignor, by mesne assignments, to American Machine and Metals, Inc., New York, N. Y., a corporation of Delaware

Application October 1, 1946, Serial No. 133,675

Term of patent 14 years

(Cl. D52—1)

To all whom it may concern:

Be it known that I, Otto Fischer, a citizen of the United States, residing in the city of Corona, L. I., county of Queens, State of New York, have invented a new, original, and ornamental Design for Flush Mounted Instrument Case, of which the following is a specification, reference being had to the accompanying drawing, forming a part thereof, in which:

Fig. 1 is a perspective view of my new design of a flush mounted instrument case, showing the cover thereof in open position;

Fig. 2 is a side elevational view thereof with the cover in closed position;

Fig. 3 is a vertical cross-sectional view taken on a diameter of the casing and with the cover in a closed position.

The characteristic features of my design reside in the portions shown by means of full lines in the drawing.

I claim:

The ornamental design for a flush mounted instrument case, as shown and described.

OTTO FISCHER.
